[57] CLAIM

The ornamental design for a pet feeding table, as shown and described.

DESCRIPTION

FIG. 1 is a front left perspective view of the pet feeding table of the present invention;

FIG. 2 is a top plan view thereof;

FIG. 3 is a reduced front elevational view thereof, the rear being identical;

FIG. 4 is a bottom plan view thereof;

FIG. 5 is a reduced left side elevational view thereof, the rear being identical;

FIG. 6 is a front, left perspective view of a second embodiment of FIG. 1;

FIG. 7 is a bottom plan view of FIG. 6, the left and right sides being identical to FIG. 5 of the first embodiment; and, FIG. 8 is a reduced front elevational view of FIG. 6, the rear being identical.
